(57) CLAIM

The ornamental design for a utility cart with integrated convenience features, as shown and described.

DESCRIPTION

FIG. 1 is a perspective view of a utility cart with integrated convenience features showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is another perspective view thereof, illustrating the lower drawer in an open position. The broken lines depicting items within the lower drawer are for illustrative purposes only, represent unclaimed subject matter, and form no part of the claimed design.

1 Claim, 8 Drawing Sheets
